APPARATUS FOR PROCESSING TEXTILES

George William Steiger, Jackson Heights, N. Y.

Application November 27, 1935, Serial No. 51,840

3 Claims. (Cl. 68—190)

The present invention relates to improved apparatus for dyeing, bleaching, wet processing, drying and similar operations as applied to textile fabrics and fibers of all kinds.

5 Although not specifically limited thereto, the present invention will be illustratively described in connection with the wet processing of yarn cones or cylinders, particularly for knitting.

In connection with yarn, particularly as used 10 for the knitting industry, it is customary to unwind yarn after it has been spun, to obtain skeins, which skeins must then be most carefully positioned or arranged in vats or tanks in which they are subjected to the action of various liquids such as dyeing liquids, bleaching liquids, desulphurizing liquids, finishing liquids, 15 sizing liquids and so forth.

It is usually necessary to subject these skeins to several handling operations in the course of 20 this treatment, and often the skeins must be removed from the tanks one or more times between various processing operations. Finally after processing, the skeins have to be rewound on cones or bobbins so that they may be conveniently employed on knitting machines.

It is among the objects of the present invention to decrease the number of handling operations necessary in wet processing yarns, particularly for the knitting industries and it is a 30 further object of the present invention to provide a means for enabling the wet processing of yarns without the necessity of unwinding them in skein form and then rewinding them back on cones or bobbins after wet processing operations, 35 which means will assure a thorough and most uniform treatment of the yarns in the form of a substantially compact mass.

It is also desirable in textile processing, particularly in connection with dyeing, bleaching, 40 finishing or sizing operations that the textile material whether in skein, cone, fabric or other form, be conveniently subjected to a plurality of treating liquids successively or alternately and it is among the further objects of the present 45 invention to provide a relatively simple system and plan for carrying out such successive treatments including a minimum of equipment and which may be installed in a relatively small space in a most compact manner.

50 In accomplishing the above mentioned objects it has been found most suitable to provide a tank or container arrangement in which yarn masses may be most conveniently stacked in say vertical piles, each yarn mass being preferably interiorly provided with a perforated holder the perforated holders being separated by plates which centrally permit communication between the interiors of the adjacent annular masses.

55 60 A hollow perforated spindle projects up

through and supports the holders in the stack and provides a central support therefor.

In my prior Patent No. 1,706,827 there is disclosed a process of effecting dyeing, rinsing and other operations in the production of textile 5 fabrics wherein the liquid in several baths is caused to flow in one direction by the action of intermittent vacuum, and then permitted to return to the tank by gravity in the intervals.

It is a further object of the present invention 10 to provide an apparatus by which a continuous vacuum may be employed to cause circulation or swishing of treating fluid backwardly and forwardly through a mass of yarn without requiring undue labor or supervision and by a 15 relatively simple, inexpensive installation subject to ready control.

In accomplishing the last mentioned object, it is only necessary to provide a relatively simple 20 vacuum system with a single vacuum tank and connected pump and with two liquid receiving and discharging expansion tanks between which the treating liquid is passed during operation.

In one preferred embodiment of the present 25 invention, a substantially continuous vacuum is first applied to one expansion tank to cause liquids first to flow outwardly through the textile materials and then to the other expansion tank to cause said liquids to flow inwardly by convenient and automatically operated valve 30 arrangements. The structure 60a is provided with a plurality of screens, strainers or similar devices which will cause a thorough mixture of the liquid passing through the conduit 56 and which may also be utilized to strain out any 35 solid particles from the liquid which may be admitted from the tank 60 into the expansion tank B.

The material carriers upon which the yarn or fabric may be wound are so positioned in the 40 treating tank or kier and the connections from the expansion tanks are so made that vacuum may be first applied to the interior of the carriers and then to the exterior of the carriers.

By assuring continually reversing flow of fluids 45 through the textile material on said carriers, a thorough penetration on the fabrics or fibers is permitted.

The valving arrangement is preferably arranged so that one or more valves may be readily 50 operated and may be arranged to permit treatment of fabrics or textile materials in a plurality of kiers or treating tanks and/or by use of a plurality of vacuum pump and vacuum tank combinations.

55 The above and other objects will appear more clearly from the following detailed description when taken in connection with the accompanying drawings, which illustrate a preferred embodiment of the inventive idea.

In the drawings:

- Figure 1 is a diagrammatic layout of a system of one of the preferred forms of the system or installment according to the present invention.
- 5 Figure 2 is a top plan view thereof on the line 2-2 of Figure 1.
- Figure 3 is a side elevational view in partial section on enlarged scale on the line 3-3 of Figure 2.
- 10 Figure 4 is a detailed transverse sectional view of one of the holding stacks upon enlarged scale, on the line 4-4 of Figure 3.
- Figure 5 is a transverse sectional view of the reversing valve device upon enlarged scale.
- 15 Figure 6 is a transverse sectional view on the line 6-6 of Figure 5 of said valve device.
- Figure 7 is a front of elevational view of said valve.
- 20 Figure 8 is an enlarged top view of the double reversing valve construction.
- Figures 9 and 10 are plan layout views similar to Figure 2 of alternative layouts showing the manner in which several treating tanks and/or several vacuum pumps may be connected in the 25 circulating system.
- Referring to Figures 1 and 2, the tank A is adapted to receive textile material, either yarn or fabric, preferably wound upon a spindle or on bobbins and cones.
- 30 Through the material in tank A, a dye solution or another treating liquid from the expansion tanks B and C, is adapted to be circulated, this circulation being effected by the controlled application of vacuum from the vacuum tank D through the automatically operated control valves E and F.
- The vacuum pump G is connected to the vacuum tank D and assures the maintenance of a desired vacuum therein. The construction and 40 the connections to the tank A are best shown in Figures 3 and 4.
- Referring to these figures, the tank or kier A consists of a shell 10 having a bottom, 11, which is supported on a foundation 12 positioned on the 45 legs 13. The bottoms of the legs 13 are provided with flanges 14 which are supported upon the flooring or other structure 15.
- The tank is provided with the cover 16 which is pivotally mounted by the ear 17 on the ear 50 18, extending upwardly from the tank structure 10, the pivot member 19 serving as the pivot mount.
- The diametrically opposite side of the tank at 20 is provided with an ear to which is pivotally connected at 21, a latch 22 which latch is provided with a threaded extension 23 receiving the clamping nut 24.
- The shank of the latch 22 is adapted to be received in the recess 25 and the nut 24 may be 55 tightened down to press the peripheral boss 26 into the packing material 27 in the recess in the upper edge of the tank structure 10.
- The lower center portion of the bottom of the tank is provided with the inlet element 28 which 60 has a conical recess 29 receiving the conical nipple 30 of the base structure 31.
- The textile material which may be in the form of a fabric or yarn is preferably wound around spindles, or wound on cones or bobbins placed on 65 said spindles, and the spindles are so connected to such annular masses of textile material that a treating liquid may be caused to be swished through the mass radially inwardly or outwardly.
- The base structure 31 is provided with a floor 70 plate 32 having the bosses 33, each of which bosses

has a tapped opening 34 therethrough receiving the perforated spindle or holder members 35.

The bosses 33 are received in the groove 36 in the lower face of the separator plate 37, the corresponding groove 38 in the upper face of the separator plate 37 receiving the perforated cylinder 39, upon which the textile material, be it fabric or yarn 40, is wound.

A series of perforated cylinders 39 carrying textile material 40 may be provided upon each 10 spindle 35, with the central perforated cylinders 39 being received in said grooves 36 and 38 in the separator plates 37, and with the outer portion of the separator plates, as indicated at 41, compressing the textile material so that all flow 15 to the spindle 35 or away from the spindle 35 will be radially through the textile material 40, as indicated by the arrows 42.

The upper end of the spindle 35 may be threaded, as indicated at 43, Figure 3, and we see the 20 wing nut 44 which enables the entire stack to be placed in compression.

The intervening plates between adjacent masses of textile material are preferably provided with 25 openings 45 to permit the treating fluid to pass from one end portion to the other end of the textile material and insure thorough treatment of the textile mass 40, both at the ends and at the middle.

The lower portion of the conical element may 30 be provided with a spider 46 receiving the rod 47 by means of a nut 48 which rod extends up through the entire stack of textile cylinders to receive the knob 49 at its upper end.

The entire stack may be lifted out of the cylinder or placed in the cylinder 10 by the knob 49, the weight of the entire stack assuring a liquid tight connection between the conical recess 29 and the conical nipple 30.

The stack of textile materials in the tank 3 40 may be of any suitable height, but it preferably does not exceed the height, as indicated in Figure 3, so that there will be an assurance that the liquid level which may vary from 50 to 51 will always be higher than the textile mass 40 during 45 the flow reversing or agitating operation.

The liquid connections are respectively made to the interior of the casing 31 by the pipe section 52 and to the exterior of the tank by the pipe section 53.

The elbows 54 and 55 are attached to the pipe sections 52 and 53, which elbows 54 and 55 are in turn connected to the pipes 56 and 57 leading to the expansion tanks B and C respectively past the hand valves 58, 59.

In operation of the tank 10 shown in Figures 3 and 4, the textile material may be loaded therein by first loading the spindles, locking the spools 40 thereon by the quick acting wing-nuts 44, and then placing the entire mass of textile materials 40 within the tank 10 and closing the cover 16 of the tank 10 is clamped by the turn nut 24 and the latch 22.

The treating liquid is first caused to flow from the tank B into the base structure 31 to the spindles 35 and radially outwardly through the textile material to the connection 57 leading to the expansion tank C.

This operation will take place in the construction indicated by the solid arrows in Figures 1 and 4.

In the reverse operation, the liquid is caused to flow from the expansion tank C radially in- 75

wardly through the textile material 40 to the expansion tank B.

This alternate reverse flow operation which may be caused to take place in the manner described, may be carried out until a sufficient treatment of the fabric or yarn is assured. The yarn may be treated this way in dyeing, sizing, finishing, degumming, drying, washing, desulphurizing, and so forth.

10 Tank B is conveniently provided with filler means 60, which enables a treating solution to be made up and placed in the tank for treatment of the textile material and mixer and/or filter 60a will assure through intermixture and/or filtration of the solution so made up in the filler means 60 and fed to the expansion tank B.

15 From the expansion tanks B and C there extend upwardly the header pipes 62 and 63, these pipes extend sufficiently upwardly so that they will be higher than the length of a column which may be raised by a vacuum, the preferred height being at least 33 to 34 feet or more.

20 These pipes 62 and 63 respectively connect to the valves E and F by which the tanks are alternately connected to vacuum and to the air assuring the circulation from one tank B to the other tank C.

25 The valve structures E and F are best shown in Figures 5, 6, 7 and 8.

30 These valves are provided with a casing 70 having the port members 71 leading to the pipes 62 and 63, to expansion tanks B and C and to the kier or tank A and also provided with the port structures 72 leading to the atmosphere and 35 73 connecting to the pipe 74 leading through the pipe 131 to the vacuum tank D.

35 The casing 70 is provided with necks of reduced diameter at 72, 73 and at these points receives the bearing sleeves 75 which at their ends are 40 provided with flanges 76 and 77 forming valve seats cooperating with the valve seat faces 78 and 79 which are clamped between the disks 80 and 81 and the end members 82 and 83.

45 The disks 80 and 81 are of sufficiently smaller diameter than the backing elements 82 and 83 to expose a sufficient annular area of the disk 78 and 79 to cooperate with the flanges 76 and 77. The extensions 84 and 85 of the sleeve members 82 and 83 ride in the bearings 86 and 87 50 which are received in the enclosure members 88 and 89 of the casing 70.

55 The central carrier rod 90 is provided with two reduced diameter portions 91 and 92 forming shoulders to abut the disks 80 and 81. The sleeve elements 82 and 83 are held in position by the head 93 and the nut 94.

60 The double valve 78, 79 as shown in Figure 5 is in the position of opening the pipe 62 to the air and cutting off the vacuum from the line 74 and it may be actuated into the other position by the extension 95 which is provided with the collar 96 and the stud 97 bearing in the boss 98 in the end casing 88.

65 The clevis element 99 embraces the extension 95, is connected to the shaft 100 at the hub 103, and provided with a bar 101 which carries an adjustable weight 102 at its upper end.

70 The hub 103 of the arm 101 is held between the support bearing members 104, 105 attached to the casing 70, in which bearing members the shaft 100 rotates.

75 The end of the shaft 100 as shown best in Figure 7, is pinned to the quadrant 106, which is provided with the ears 107 and 108 respectively receiving adjusting stop screws 109 and 110 which

may be locked in position by lock nuts 111 and 112.

By adjusting the screws 109 and 110 of Figure 7, it is possible to regulate the length of the periods during which the vacuum is supplied 5 to each of the expansion tanks B and C.

Rotatably mounted on the shaft 100 is the lever 113 having the wedge-like contact portion 114 and the slotted extension 115, the slot of which receives the pin 116. The pin 116 carries 10 the washer 117 and the split pin 118. The pin 116 is fixed to the gear 119 which is pivotally mounted on the shaft 120 and rotates as indicated by the arrow 121 in Figure 7.

The shaft 120 has a bearing, as indicated at 15 122 in Figure 6 in the end member 88.

The worm 123 which meshes with the gear 119 is mounted on the shaft 124 which is carried 20 in the bracket 125 bolted as indicated at 126 in Figure 6 to the lower part of the end casting 88.

The shafts 124, (see Figure 8) of the valves E and F are driven by the gears 127 which mesh with the pinion 128 which is driven by the shaft 129 of the electric motor 130. 25

In operation, the motor 130 is continuously operated during wet treatment and causes continuous rotation at a predetermined R. P. M. of the gears 119, as a result the valves 78 and 79 will be actuated first to apply vacuum to the tank B and atmospheric pressure to the tank C and atmospheric pressure to the tank B. This application of vacuum may be continued to cause a 30 change in liquid level from 50 to 51 in the tank A, (see Figure 3) the liquid level first rising and then falling.

The swishing of liquid radially outwardly and radially inwardly, as indicated by the arrows 42 (see Figure 4) will assure a most satisfactory 40 treatment of the fabric and most thorough processing thereof.

As indicated in Figure 1, the two vacuum lines 74 join in a single line 131 which leads to the vacuum tank D. 45

In Figure 9 is shown a slightly different layout in which the two treating tanks or kiers A' are each provided with two expansion tanks B' and C', similarly functioning parts in the embodying of Figure 9 being indicated by the same numerals 50 primed.

In the structure of Figure 9, the lines 62 and 63 instead of being connected directly to the valves E', F', are connected thereto by the switch pipes 140, 141. The switch pipes 140 and 141 55 may be as long as desired and be connected to as many conduits leading to various liquid treating tanks or systems as shown in Figure 9, as may be desired.

In Figure 10, as shown schematically, is an 60 other system in which similarly functioning parts are indicated by the same numerals provided with a superior 2.

In the embodiment of Figure 10, two pumps G² are provided and they are caused to operate 65 on the vacuum tanks D² which are connected together by the pipe 142 provided with the hand valves 143, and 145.

Two sets of control valves E² and F² are provided. 70

In the layout shown in Figure 10, by opening of the valves 143, 145, 146, 147, 148 and 149 and 150, it is possible to operate the tanks A² in Figure 10 in tandem.

As shown in Figure 10, the expansion tanks B² 75

may be connected together by the line 151 and the valves 146 and 147.

The expansion tanks C² may be connected together past the valves 150 and 152 through the line 153.

The two systems may be cut off from one another and operated independently by closing the valves 143, 145, 146, 147, 148, 149, 150 and 152.

It is thus apparent by the arrangement shown in Figure 10, a double vacuum or double control may be applied to the expansion tanks or other suitable rearrangement may be made for special operations and purposes.

In preparing the solution in the expansion tanks B in Figure 1, the solution may be made up in the smaller tank 60 and thorough mixture may be assured by passing through the mixer and filtering device 60a.

Referring to Figure 4, although the tops of the spindle 35 may be closed in various manners, the plug 200 shown in Figure 4 has been found to be particularly suitable.

It is apparent, according to the arrangements shown in Figures 9 and 10, that a large number of combinations of treating tanks A, expansion tanks B and C, control valves E and F and vacuum tanks D may be made and it is intended to include all such alternative arrangements and systems within the scope of the present invention.

The switch pipe arrangement 140 and 141 may also be utilized in the arrangement shown in Figure 1 or in the arrangement shown in Figures 1 and 2.

Before placing the carrier 31 with its loaded cylinders 40 into the tank A, the tank is preferably filled with clean water without the treating chemical or material to be added up to the level 210 (see Figure 3).

This water may be heated to the desired temperature by the direct and indirect heating coils 211 and 212 after the cover 16 has been closed.

The treating chemical then is fed into the treating solution through the auxiliary feeding tank 60 in which the dye, bleach or other material is placed together with the necessary quantity of water, the initially concentrated material being formed in said auxiliary tank 60.

The outlet valve 213 (see Figure 1) may be opened during the application of vacuum to the expansion tank B to permit the concentrated treating solution to be drawn into the header pipe 62 and when the treating solution has been entirely drawn from the tank 60, the valve 213 may then be closed.

Then, upon application of the vacuum to the opposite tank C, this treating solution, the mixture of the chemical from the tank 60 and the water from the tank A, will be drawn downwardly from the pipe 62 and the expansion tank B through the mixer and filter 60a which may take the form of a cylindrical device provided with a series of perforated plates, the perforations of which are all set so as to cause a maximum turbulence of the liquid in passing therethrough.

The treating liquid containing the chemical then flows through the pipe 56 into the kier or tank A from which solution is being drawn by the pipe 57 into the expansion tank C and the header pipe 63.

Then, upon the reverse operation, the flow will be from the header pipe 63 and the expansion tank C through the pipe 57 into the tank A through the textile material 40 and then through the pipe 56 to the expansion tank B and the

header 62. These reversals will continue until the proper amount of treatment has taken place.

By immersing the textile material in plain water and then by first adding the treating chemical to the circulating fluid, as it is being alternately reversed, by the action of the vacuum, assurance is had of a more uniform treatment of the textile material by the treating chemicals.

After the tank has been loaded by the carrier 31, a tight action between the nipple and the recess 29 is assured by tightening the hand wheel 220 of Figure 3 which connects to the rod 223, said rod having a threaded portion 222 extending through a tap bore in the boss 224.

The lower end of the rod 223 is connected to a contact member 225 which is adapted to be pressed down upon the knob 49 and presses the nipple 30 tightly into the recess 29 providing a liquid tight joint.

To eliminate the air which may collect in the tank A, after the carrier 31 and the textile material 40 have been immersed therein, the bleeder pipe 226, provided with the valve 227 may be provided, the said bleeder pipe in the embodiment shown in Figure 3 being connected to the boss 224 which is at the highest point of the tank.

As shown in Figure 1, the expansion tanks B and C are preferably provided with the sight glasses 230 so as to enable determination of the liquid level therein.

When it is desired to wash the textile material 40, in the tank A, free of the treating solution or to dry the same, the valve connections 231 and 232 may be both or alternately employed (see Figure 1). The washing liquid may also be fed into the tank 60 when the vacuum is being applied to the tank C, with the valve 213 being closed through each reversal of the vacuum.

Washing fluids and other treating liquids which are to be wasted may be conveniently dumped through the valve T-connections 58, 59, which are best shown in Figure 2.

As indicated in Figure 2, the valve connections 58, 59 on the line 56, 57 each take the form of a T the stem 240 of which is provided with the hand valve 241 and the automatically operating check valve 242. The end of the T is connected to waste by means of the tail pipe 243.

When vacuum is applied to the tank 56 or 57, to draw liquid toward the expansion tank, a check valve 242 will be closed so that no flow will take place through the tail pipe 243.

However, when the valve 241 has been opened and liquid is flowing toward the tank A from an expansion tank B or C the check valve 242 will be automatically opened permitting the waste liquid to be discharged to a sewer or other place of disposal.

Although yarns of all characters may be treated according to the present invention, the process and apparatus of the present invention has been found particularly advantageous in application to woolen or worsted yarns for knitting purposes.

These yarns if not most carefully treated in ordinary wet processes will tend to stretch if subjected to any particular amount of liquid pressure and the quality will deteriorate. According to the present invention, these yarns are wet processed without being stretched and without the use of liquid pump pressure, the alternating application of vacuum being sufficient to 75

draw the treating fluid gently through the textile mass 40 without injury.

It is to be understood that many modifications and arrangements may be made within the scope of the present invention without departing from the spirit of the invention and it is intended to include all kinds of arrangements and constructions within the scope of the appended claims.

10 I claim:

1. A system for dyeing cotton and woolen yarns or for treating such yarns with other liquids or fluids, said yarns being wound concentrically upon elongated hollow members provided with flow openings, comprising a main tank to receive said members, said main tank having liquid connections to adjacent the bottom thereof to admit or remove a dye liquor or other fluid, and said yarns being at all times immersed in said dye liquor or other fluid in said tank, said tank also being provided with means to connect said hollow members interiorly at one end to one of said connections, the other ends of said hollow members being closed off and the other connection opening into the main tank exteriorly of said yarn, so that said dye liquor or other fluid will be compelled to flow through said concentrically wound yarn in passing toward or from said interior connection, expansion tanks to receive dye liquid or other fluid from said connections positioned above said main tank, each having a conduit extending from the bottom thereof to one of said connections, a part of the dye liquor or other fluid in said main tank being alternatively drawn through said connections between said expansion tanks inwardly and outwardly through the concentrically wound yarn to and from said hollow members with changing of the level of the dye liquor or other fluid in said tank during said circulation without said level at any time uncovering said yarn, a single central vacuum source, conduits connecting said source to the upper portions of said expansion tanks, valve means on said conduits alternately to open the conduits to the atmosphere and to close the conduits from the atmosphere and open them to said source and automatically actuated means to operate said valve means to cause said source to be connected at all times to one of said expansion tanks and the atmosphere to the other of said expansion tanks, whereby said dye liquor or other fluid will at all times be sucked through said concentrically wound yarn inwardly or outwardly by said source.
2. A system for dyeing cotton and woolen yarns or for treating such yarns with other liquids or fluids, said yarns being wound concentrically upon elongated hollow members provided with flow openings, comprising a main tank to receive said members, said main tank having liquid connections to adjacent the bottom thereof to admit or remove a dye liquor or other fluid, and said yarns being at all times immersed in said dye liquor or other fluid in said tank, said tank also being provided with means to connect said hollow members interiorly at one end to one of said connections, the other ends of said hollow members being closed off and the other connection opening into the main tank exteriorly of said yarn so that said dye liquor or other fluid will be compelled to flow through said concentrically wound yarn in passing toward or from said interior connection, expansion tanks to receive dye liquid or other fluid from said connections positioned above said main tank, each having a con-

duit extending from the bottom thereof to one of said connections, a part of the dye liquor or other fluid in the said main tank being alternately drawn through said connections between said expansion tanks inwardly and outwardly thru the 5 concentrically wound yarn to and from said hollow members with changing of the level of the dye liquor or other fluid in said tank during said circulation without said level at any time uncovering said yarn, a single central vacuum source, 10 conduits connecting said source to the upper portions of said expansion tanks, valve means on said conduits alternately to open the conduits to the atmosphere and to close the conduits from the atmosphere and open them to said source and 15 automatically actuated means to operate said valve means to cause said source to be connected at all times to one of said expansion tanks and the atmosphere to the other of said expansion tanks, whereby said dye liquor or other fluid will 20 at all times be sucked through said concentrically wound yarn inwardly or outwardly by said source, said hollow members being positioned and clamped upon perforated tubular members opened at one end to said interior connection and 25 closed at the other end.

3. A system for dyeing cotton and woolen yarns or for treating such yarns with other liquids or fluids, said yarns being wound concentrically upon elongated hollow members provided with flow openings, comprising a main tank to receive said members, said main tank having liquid connections to adjacent the bottom thereof to admit or remove a dye liquor or other fluid, and said yarns being at all times immersed in said dye liquor or other fluid in said tank, said tank also being provided with means to connect said hollow members interiorly at one end to one of said connections, the other ends of said hollow members being closed off and the other connection opening into the main tank exteriorly of said yarn, so that said dye liquor or other fluid will be compelled to flow through said concentrically wound yarn in passing toward or from said interior connection, expansion tanks to receive dye liquid or other fluid from said connections positioned above said main tank, each having a conduit extending from the bottom thereof to one of said connections, a part of the dye liquor or other fluid in the said main tank being alternately drawn through said connections between said expansion tanks inwardly and outwardly thru the concentrically wound yarn to and from said hollow members with changing of the level of the dye liquor or other fluid in said tank during said circulation without said level at any time uncovering said yarn, a single central vacuum source, conduits connecting said source to the upper portions of said expansion tanks, valve means on said conduits alternately to open the conduits to the atmosphere and to close the conduits from the atmosphere and open them to said source and automatically actuated means to operate said valve means to cause said source to be connected at all times to one of said expansion tanks and the atmosphere to the other of said expansion tanks, whereby said dye liquor or other fluid will at all times be sucked through said concentrically wound yarn inwardly or outwardly by said source, said hollow members being positioned and clamped upon perforated tubular members opened at one end to said interior connection and closed at the other end, said tubular members being vertically positioned within said tank.
